UNITED STATES PATENT OFFICE.

ROBERT M. MILLER, OF MILWAUKEE, WISCONSIN.

VISE.

1,392,434.

Specification of Letters Patent.

Patented Oct. 4, 1921.

Application filed November 22, 1920. Serial No. 425,692.

To all whom it may concern:

Be it known that I, ROBERT M. MILLER, a citizen of the United States, and resident of Milwaukee, in the county of Milwaukee and State of Wisconsin, have invented certain new and useful Improvements in Vises; and I do hereby declare that the following is a full, clear, and exact description thereof.

My invention relates broadly to new and useful improvements in tools and has particular application to bench or other types of vises.

Heretofore practically all metal vises have had a considerable number of cast parts which necessitates the formation of suitable patterns. However, it is the purpose of this invention to provide an efficient vise which may be formed almost entirely of standard metallic parts or parts of materials which are in every day use.

It is likewise an object of the invention to provide a device, the principles of which may be employed in an ordinary carpenter's bench vise, or in a metal worker's vise.

With these general objects in view the invention resides in the novel features of construction, combination and arrangements of parts which will be hereinafter more particularly described and claimed, and shown in the accompanying drawing wherein:

Figure 1 represents a plan view, partly in section, of a vise constructed in accordance with the invention, and

Fig. 2 is a longitudinal sectional view taken on the plane of the line 2—2 of Fig. 1.

Referring more particularly to the drawing, it will be seen that the stationary jaw of my improved vise is formed by the jaw flange 1 of a right angular plate 2, the same being cut from a length of angle bar stock.

The other flange 3 of the angle plate forms an attaching portion whereby the vise may be secured by a suitable bolt or the like 4 to a support 5, such as a work table or bench.

The movable jaw of the device is formed of a flat jaw plate 6 having a surface area substantially equal to that of the stationary jaw and supported upon the ends of a pair of guide rods 7. These rods 7 are spaced apart and are designed to slide through spaced openings in the jaw flange 1 and through openings alined therewith in a guide plate 8. As shown the guide plate 8 is formed of the intermediate portion of a Z plate, one horizontal flange 9 of which is adapted to be secured to the attaching flange

3, whereas the other horizontal flange 10 overlies the head of the bolt 4 and portions of the guide rods 7.

A feed screw 11 is also connected with the jaw plate 6, it being extended therethrough and having a sleeve 12 secured upon its outer ends by a transverse handle bar 13, whereby a head is formed. The portion of the sleeve adjacent the jaw plate 6 has an annular groove 14 in which the lip 15 of a retaining plate 16 is disposed, said plate being secured by a set screw 17 to the lower portion of the jaw plate 6. As the result of such construction the head and feed screw are readily rotatable with respect to the jaw plate, but are held against axial movement away from or through the same.

The inner portions of the feed screw being disposed parallel to the guide rods 7, are slidable through an opening 18 in the jaw flange 1 and threadedly movable through an opening alined therewith in the plate 8. Thus by rotating the head 12 and the feed screw 11, the movable jaw of the vise is shifted toward and away from the stationary jaw. The portions of the feed screw between the jaw flange 1 and the guide plate 8 are covered by the flange 10 whereby chips and metal scraps or the like are prevented from falling upon the screw threads of the feed screw.

When the vise is to be used for carpentry work and is mounted on a wood worker's bench, the upper edge of the jaws are preferably disposed and flushed with the surface of the bench. In such a case the flange 10 of the Z plate may be provided with attaching ears 19 for securement to the under surface of the top 20 of the work bench. Such an arrangement of parts is disclosed in dotted lines in the figures of the drawing.

From the foregoing description it will be evident that I have invented a very simply constructed device which will be quite efficient in operation and one which can be inexpensively manufactured. Various changes can be made in the varying proportions of the several parts of the invention without departing from the principles thereof or sacrificing any of the advantages.

I claim as my invention:

1. In a device of the character described, an angle iron, means for securing the same to a bench with one flange substantially horizontal and the other flange substantially vertical; a Z plate secured to said angle iron

with its intermediate portions substantially vertical, a movable jaw having guide rods attached thereto and passing horizontally through said angle iron and **Z** plate, and 5 slidably engaging the same, a threaded rod rotatably mounted in said movable jaw and held against longitudinal movement therein, said threaded rod passing horizontally through said angle iron and **Z** plate and 10 threadingly engaging the latter, and means for rotating said threaded rod to open and close said jaws.

2. In a device of the character described, an angle iron, means for securing the same 15 to a bench with one flange substantially horizontal and the other flange substantially vertical, a **Z** plate secured to said angle iron with its intermediate portion substantially vertical, a movable jaw having guide rods 20 attached thereto and passing horizontally through said angle iron and **Z** plate, and slidably engaging the same, a threaded rod rotatably mounted in said threaded jaw and passing horizontally through said angle iron 25 and **Z** plate, and threadingly engaging the latter, means for rotating said threaded rod and an abutment secured on the threaded

rod outside of the movable jaw to limit the outward movement of the latter.

3. In a device of the character described, 30 an angle iron, means for securing the same to a bench with one flange substantially horizontal and the other substantially vertical, a **Z** plate secured to said angle iron and its intermediate portion substantially vertical, a movable jaw having guide rods attached thereto and passing horizontally through said angle iron and **Z** plate, and 35 slidably engaging the same, a threaded rod rotatably mounted in said movable jaw and passing through said angle iron and **Z** plate and threadingly engaging the latter, means for rotating said threaded rod, a sleeve secured to said threaded rod and having a 40 circumferential groove therein, and a plate 45 secured to said movable jaw and having a lip engaging said groove, whereby said threaded rod is held against longitudinal movement when rotated.

In testimony that I claim the foregoing I 50 have hereunto set my hand at Milwaukee, in the county of Milwaukee, and State of Wisconsin.

ROBERT M. MILLER.
